UNITED STATES PATENT OFFICE.

SAMUEL L. BLIGH, OF CUSTARD'S, PENNSYLVANIA.

FIRE-KINDLER.

SPECIFICATION forming part of Letters Patent No. 611,232, dated September 27, 1898.

Application filed September 25, 1897. Serial No. 652,993. (No model.)

To all whom it may concern:

Be it known that I, SAMUEL L. BLIGH, a citizen of the United States, residing at Custard's, in the county of Crawford and State of Pennsylvania, have invented certain new and useful Improvements in Fire-Kindlers; and I do hereby declare that the following is a full, clear, and exact description of the same, reference being had to the annexed drawings, making a part of this specification, and to the letters of reference marked thereon.

The present invention has for its object to provide a simple and effective device adapted to be placed in a heating or cooking stove or a grate and supplied with oil which is vaporized and burns in the stove or grate for the purpose of igniting and kindling a fire therein when used with the ordinary fuel or used as a heating medium in place of the ordinary fuel.

The invention consists in a device of the above character constructed substantially as shown in the drawings and hereinafter described and claimed.

Figure 1 is a perspective view of my improved device; Fig. 2, a horizontal section thereof; Fig. 3, a detail cross-section taken through the oil-chamber.

In the accompanying drawings, A represents the cross-head having the extension F, which is cast or otherwise formed therewith, said cross-head having a chamber B for the oil, which is closely and tightly packed with particles of metal of uniform size, as shown at C; or metal filings or pebbles may be used or other suitable matter which has a tendency to disintegrate and subdivide the volume of oil which enters the chamber. The oil-chamber after being properly packed with the filling, as above described, the open ends of the chamber are closed by means of screw-plugs a, which engage interior screw-threads in the ends of the chamber.

A supply-pipe D, leading from a suitable tank or receptacle to contain the oil, connects with the extension F of the device and communicates with the oil-chamber B. The extension F protects the end of the pipe D from being burned off when in the fire-box from the great heat to which it is exposed.

The pipe D, which connects in any suitable manner with an elevated tank or receptacle, as hereinbefore described, is protected by an outer pipe E, which surrounds the same, with its end fitting over and around the neck b of the extension F.

Holes c are formed in any part of the cross-head A, their location being governed by the use to which the device is to be applied, said holes communicating with the interior of the oil-chamber B and having pins d embedded in the filling C, with their ends projecting out through the holes a short distance. The pins prevent the openings from being interfered with by the ashes in the stove or grate when used as a kindler; also, when the pins are heated they assist in forming the gas, the gas after being generated passing out through the holes and guided upward by the pins.

The supply of oil to the chamber is regulated in the usual manner either by a stop-cock or other well-known means.

The device may be changed in form as found desirable without departing from the spirit of the invention.

Having now fully described my invention, what I claim as new, and desire to secure by Letters Patent, is—

In a fire-kindler, a cross-head having a longitudinal chamber B provided with openings c through its top; the plugs a for closing the ends of the chamber, a filling placed in the chamber to receive oil, an extension F projecting at an angle from the cross-head and provided at its end with an opening, and the supply-pipe which is inserted in the opening in the extension, combined with an outer pipe E which protects the supply-pipe, and pins d which project from the openings c in the cross-head, and which have their inner ends embedded in the filling in the chamber, substantially as shown and described.

In testimony that I claim the above I have hereunto subscribed my name in the presence of two witnesses.

SAMUEL L. BLIGH.
